Primary Examiner—Paula A. Mortimer(74) *Attorney, Agent, or Firm*—Sughrue Mion, PLLC(57) **CLAIM**

The ornamental design for the protrusions on a belt and a belt, as shown and described.

DESCRIPTION

FIG. 1 is a perspective view of the front, right, and top sides of the protrusions of a belt and a belt showing my new design;

FIG. 2 is a front elevational view thereof;

FIG. 3 is a rear elevational view thereof;

FIG. 4 is a left side elevational view thereof, the right side being a mirror image;

FIG. 5 is a top plan view thereof; and,

FIG. 6 is a bottom view thereof.

In FIGS. 1–6, the belt is an integral part of the claimed design.
